CLAIM

The ornamental design for a removable lid jar, as shown and described.

DESCRIPTION

FIG. 1 is a top perspective view of a removable lid jar showing our new design;

FIG. 2 is a front elevation view thereof, the rear elevation being identical;

FIG. 3 is a top plan view thereof; and,

FIG. 4 is a bottom plan view thereof.

The sidewall of the jar has been shown fragmented to indicate indeterminate length.

The broken lines shown in the drawings represent unclaimed environment and are for illustrative purposes only, forming no part of the claimed design.
